UNITED STATES PATENT OFFICE.

CHARLES F. HANSEN, OF LOS ANGELES, CALIFORNIA.

BAG.

Application filed February 19, 1924. Serial No. 693,882.

This invention relates to improvements in article carrying cases or bags.

The primary object of this invention is the provision of an article carrying case or bag which is adapted to carry relatively heavy loads, and which includes a novel arrangement of parts to best support the load and reinforce the same, whereby excessive wear will not take place upon any particular part, and the case may ably support the load without distorting the neat appearance of the same.

A further object of this invention is the provision of a novel form of case which is particularly well adapted for carrying tools and the like, embodying a novel handle construction to effectively support the load from the bottom of the case.

A further object of this invention is the provision of novel closure means for hand bags, which will permit easy access to the contents of the bag, and best retain the bag in its natural shape.

Other objects and advantages of this invention will be apparent during the course of the following detailed description.

In the accompanying drawings, forming a part of this specification, and wherein similar reference characters designate corresponding parts throughout the several views,

Figure 1 is a side elevation of the improved article carrying case or bag, showing a portion thereof removed to clearly indicate the bottom construction of the bag.

Fig. 2 is a side elevation of the bag, showing the opposite side to that illustrated in Figure 1.

Fig. 3 is an end elevation of the improved bag, showing it in closed relation.

Fig. 4 is an end elevation of the improved bag, showing the closure thereof open.

Fig. 5 is a fragmentary cross sectional view taken through the lower portion of the bag.

Fig. 6 is a fragmentary cross sectional view taken through the upper portion of the bag.

Fig. 7 is a perspective view of a novel type of reinforcing or bracing member which is used in the closure of the improved bag.

Fig. 8 is a perspective view of a transverse bottom brace used in connection with the supporting means for the bag.

Fig. 9 is a cross sectional view taken substantially on the line 9—9 of Figure 4.

In the drawings, wherein for the purpose of illustration is shown but the preferred embodiment of this invention, the letter A may generally designate the improved case or bag, which may include an article carrying body portion 10; closure means 11; and supporting means 12 for carrying of the bag or case.

Referring to the construction of the article carrying or body portion 10, the same includes front and rear walls 15 and 16 respectively; a bottom wall 18; and end walls 19. It is preferred that the front and rear walls and bottom wall be of one piece construction, and the end walls 19 are stitched to the marginal edges of the front, rear, and bottom walls. The end walls 19 are preferably fluted, or accordion pleated to render the same transversely collapsible at their upper portions, although the pleats do not extend to the lower portions of said end walls, as is illustrated in the drawings. It is preferred that each end wall 19 have a longitudinal pleat 20, midway of the side edges of said end walls, which extends outwardly of the end wall, and intermediate pleats 21 are provided at each side of the middle pleat 20; the pleats 21 extending inwardly of the compartment of the case portion 10. The pleats 20 and 21, at their upper ends are secured by means of transversely extending rivets 23, which insures that the pleats will retain their definite location upon the end walls.

A pair of metal braces 30 are placed with in the compartment of the bag transversely over the bottom wall 18 thereof; each of these braces 30 including the upstanding end portions 31 which overlie the interior surfaces of the front and rear walls of the article carrying portion 10. These braces are of metal, and reinforce the bottom wall against buckling, and are cooperatively disposed with respect to the strap supporting means 12, as will be subsequently described. An interior lining 35 is secured within the case portion 10, over the bottom wall 18 thereof, and which includes upstanding side portions secured to the side and end walls for a short distance therealong, substantially as is illustrated in Figure 5 of the drawings. It is preferred that a cardboard bottom or layer 36 be provided between the lining 35 and the bottom wall 18; this cardboard 36 being disposed over the transverse braces 30,

and thus providing a means for insuring an even inside surface for the bag or case, and properly protecting the same.

The closure means 11 of the improved case A preferably comprises a reinforcing member 40, which is formed of metal, and U-shaped in cross section. This member 40 includes the relatively narrow rear wall 41; top wall 42; and front wall 43, which is 10 wider than the rear wall 41. The length of the walls is the same, and the front wall 43 is preferably provided with substantially L-shaped lugs 45 outstruck therefrom, and bent parallel toward the ends of the member 40 to provide pockets or slots for reception of portions of the supporting means 12 to properly retain the latter in place, as will be subsequently mentioned. The reinforcing channel member 40 is stitched between 20 the outer and inner layers 47 and 48 of flexible material, preferably of leather, or material analogous to that of which the carrying portion 10 is constructed. The layers 47 and 48 extend considerably below the 25 marginal edge of the rear wall 41 of the reinforced member 40, and are stitched, as by a line of stitching 49, immediately below the lower edge of the wall 41; this stitching being upon the rear wall 16 of the bag portion 10, as the means for hingedly connecting the closure member 11 to the carrying portion 10. The channel member 40 is, of course, so arranged with respect to the top of the carrying portion 10, that the upper 35 portion of the carrying portion 10 may be received within the channel of the member 40 so that the front wall 43 of the reinforcing member 40 will overlie the front wall of the carrying portion 10 when the closure 40 member 11 is shut. It is to be noted that the ends of the closure member 11 overhang for a short length the top edges of the carrying portion 10, to completely close the case body 10, as is illustrated in Figures 1 and 2. 45 of the drawings. It is preferred that the closure 11 at the front corners thereof be provided with suitable snap fasteners 50, which may cooperate with appropriate portions secured on the front wall of the article carrying portion 10, as can readily be understood. The channel member 40 is, of course, completely stitched within the outer and inner folds or layers 47 and 48, and any additional stitching of these folds to 50 each other and to the rear wall 16 of the casing may be provided, as is illustrated in the drawings.

The supporting means 12 preferably includes a single strap or other piece of material, which is looped or bent intermediate its ends to provide a handle 60, and from the handle 60 strands 61 and 62 extend over the rear wall 16 of the carrying portion 10, and are secured to this wall, as by rivets 63 or the like. The uppermost rivets 63 are

located somewhat below the hinged junction of the closure 11 with respect to the carrying portion 10, so that the handle 60 at the rear wall of the case A is free to be moved. The strap from the strands 61 and 62 is brought beneath the bottom wall of the carrying portion 10, as in lengths 65, which are placed immediately below the transverse metal braces 30. Several of the rivets 63 are so located that they prevent shifting 70 of the portions 65 along the bottom wall, and if desired rivets may secure the portions 65 to the metal braces 30, although it is not necessary to provide such construction. The strap of the supporting means 12 is extended upwardly along the front wall 15 of the case portion 10, in strands 68 and 69, disposed in converging relation toward the top of the case portion 10. The strands 68 and 69 are secured to the front wall 15 by means of rivets 70, analogous to the rivets 63 above described. The strand 68 is relatively short, and at its upper end is provided with a connecting buckle 71 which extends to a point on the front wall 15 just below the lower edge of the front wall of the closure member 11 when the latter is closed on the case. The strand 69 continues upwardly and may be looped or bent to provide a handle 75; the strap being provided with a portion 77 having apertures therein for adjustable connection to the buckle 71, so that the handle 75 may be adjusted, depending upon the quantity of articles within the case, so that the user may have a convenient grasp upon the handles 60 and 75. The handle 60 will, of course, always be of the same size and retained in substantially the same position. The handle 75 is adjustable, however, and to retain the same in a definite location with respect to the case when the lid or closure 11 is shut, the side portions of the handle 75 may be received within the slots or pockets provided by the outstruck lugs 45 of the closure member 40, as substantially illustrated in Figure 1 of the drawings. If the contents of the case A are such as to bulge the side walls outwardly, in order to make the handles 60 and 75 meet, as is illustrated in Figure 3 of the drawings, it may be necessary to adjust the handle 75 by means of connection of the strand 77 in the appropriate place upon the buckle 71.

From the foregoing description of this invention it is apparent that a case has been provided which is properly reinforced at necessary points. The conventional cases for carrying tools and other heavy articles have the handles thereof secured adjacent the top of the case, so that the strain does not support the load at the proper location. However, with the means 12 provided for the case A the load is supported not only from the side walls of the carrying portion 10, 120

but from the bottom wall, and the bottom wall of the case is prevented from buckling incident to the support of this load by means of the transverse reinforcing member 30, 5 thus insuring that the bottom will always keep its shape, and in contra-distinction to the ordinary case. The handles 60 and 75 always have a definite relation with respect to the case, and the lugs 45 of the closure 10 member are novel for definitely locating the handle 75. These lugs 45 may be suitably covered by means of portions of the inner and outer folds or linings 47 and 48, which may be glued to the lugs or guard portions 15 45.

Various changes in the shape, size, and arrangement of parts may be made to the form of the invention herein shown and described without departing from the spirit of 20 this invention or the scope of the claims.

I claim:—

1. In a case, the combination of a carrying portion providing a compartment therein and including a bottom wall, transverse 25 metal braces connected to the carrying portion at the inside surface over the bottom wall, and supporting means including a strap secured exteriorly about the bottom wall of the carrying portion and extending 30 along the transverse braces so that support of the carrying portion and its load by said supporting means may be effected without buckling of the bottom wall.

2. A bag of the class described comprising 35 a carrying portion, a closure member hingedly connected at the side of the carrying portion so that it may be swung laterally of said side, handle means connected to the carrying portion, and means on said 40 closure member for cooperation with the handle means to facilitate carrying of the bag.

3. In a device of the class described, the 45 combination of a case including a carrying portion, a closure member for the carrying portion including a pair of outstanding lugs, and handle means for the carrying portion adapted to be received by the lugs when the closure member is shut to definitely locate 50 the handle means with respect to the carrying portion and closure member to facilitate carriage of the case.

4. In an article carrying case, the combination of a carrying portion including front 55 and rear walls, and closure means for the carrying portion including outer and inner flexible folds and a rigid channel member

stitched between said folds, said folds being connected to the rear wall of the carrying portion so that the closure means may 60 hingedly swing laterally of the rear wall to entirely open the carrying member, the upper portion of said carrying member adapted to be received within the groove of said channel portion of the closure means when 65 the latter is shut.

5. In a device of the class described, the combination of a carrying portion including front and rear walls, closure means hingedly connected to the rear wall including a rigid 70 section having outstruck spaced lugs thereon, a handle of fixed character connected to the case at the rear wall thereof, and an adjustable handle connected to the case at the front wall thereof, said adjustable handle 75 adapted to be received by the lugs of the closure member when the latter is shut to properly position the adjustable handle with respect to the fixed handle.

6. In a bag of the class described, the 80 combination of a flexible carrying portion including side walls, a bottom wall, and collapsible end walls, a closure for the carrying portion including a channel shaped rigid metal member open at the ends thereof 85 and embedded between layers of a flexible material, said flexible material at one edge of the channel extending outwardly therefrom and being secured at the outer side to one of said side walls to hingedly support the closure member whereby when the side walls of the carrying portion are collapsed the closure member may be swung to enclose the upper portion of the carrying portion, and a strap secured about the side walls and below 90 the bottom wall and at its ends providing 95 handles at opposite sides of the bag.

7. In a case of the class described the combination of a flexible carrying portion including elongated side walls, a bottom wall, and fluted collapsible and extensible end walls, said carrying portion upwardly thereof providing an opening which may be increased and decreased by relative movement of the side walls, an elongated channel 105 shaped metal closure providing an elongated pocket therealong open at the ends of said closure, and means hingedly connecting said lid with one of the side walls of the flexible carrying portion whereby when the 110 same is swung it may enclose and seal the upper part of the side and end walls when the said end walls are collapsed.

CHARLES F. HANSEN.
